GAME BOARD

Robert E. Rumpf, Jr., 2706 Eisenhower Drive,
South Bend, Ind.

Filed May 3, 1965, Ser. No. 85,058

Term of patent 3½ years

(Cl. D34—5)

FIG. 1

FIG. 2

I claim:

The ornamental design for a game board, substantially as shown.
